ARCING GAP

Ralph Higgins, Akron, Ohio, assignor to The Ohio
Brass Company, Mansfield, Ohio, a corpora-
tion of New Jersey

Application July 27, 1935, Serial No. 33,533

6 Claims. (Cl. 175—30)

This invention relates to arcing gaps for protecting electrical apparatus from excessive voltage and is illustrated as applied to a gap similar to that disclosed in Patent No. 2,011,136, granted

5 August 13, 1935.

One object of the invention is to provide means for quickly interrupting the arc across the gap before the current flowing in the arc has time to trip the main circuit breakers.

10 A further object of the invention is to provide an arcing gap equipped with arc interrupting mechanism in which the action of the interrupting means does not interfere with the operation of the gap for recurrent surges.

15 A further object of the invention is to provide an arcing gap having means connected therewith for automatically interrupting the arc after each of a series of recurrent operations of the gap.

20 A further object of the invention is to provide an arcing gap equipped with arc interrupting means adapted for repeated operation, the gap being operative to protect the connected apparatus even after the interrupting means has been exhausted by repeated operations.

25 A further object of the invention is to provide a device of the class named which shall be of improved construction and operation.

Other objects and advantages will appear from the following description.

30 The invention is exemplified by the combination and arrangement of parts shown in the accompanying drawings and described in the following specification, and it is more particularly pointed out in the appended claims.

35 In the drawings:

Fig. 1 is a diagrammatic view illustrating one embodiment of the invention.

Figs. 2 and 3 are views similar to Fig. 1 showing other forms of the invention.

40 Fig. 4 is an elevation of arcing gap apparatus showing one embodiment of the form of the invention illustrated diagrammatically in Fig. 3.

Fig. 5 is an end view looking from the right in Fig. 4.

45 Fig. 6 is a fragmentary top plan view of the arc extinguishing portion of the apparatus shown in Fig. 4.

The primary function of a control gap, such as that shown in the Austin patent referred to above, 50 is to relieve the high tension line to which it is connected of abnormal lightning and switching surges before such surges have done serious damage. Sometimes, in order to afford adequate protection against insulation breakdown or flash- 55 over of station equipment, it is necessary to set the

gap quite low. Naturally a low setting of the gap will cause it to function quite frequently. With one terminal of the gap solidly grounded, each operation of the gap requires the power arc, which follows flashover of the gap, to be interrupted by the operation of one or more of the main line circuit breakers. The operation of the line circuit breakers is sometimes very objectionable, especially when large blocks of power are involved and when interruption of power service entails great losses to the customers. Also, on some lines that are not equipped with suitable ground relays or high speed over-load relays, the main circuit breakers will often require some time before they will open. In such cases the long duration of the power arc is apt to do considerable damage to the arcing tips and other parts of the gap.

To overcome these difficulties, the present invention provides a high voltage fuse or some other quick acting circuit breaker in series with the control gap to clear the control gap before the main line circuit breakers have a chance to open and before the arc can do any damage to the gap parts. If such a fuse or quick operating circuit 20 interrupter were used alone in series with the control gap, the gap would no longer be solidly grounded after operation of the interrupter and thus should another surge follow immediately, before the fuse can be renewed, which happens 25 quite frequently, the control gap would be inoperative and the desired protection would not be afforded.

To overcome this difficulty, the present invention provides an arrangement which is shown 35 diagrammatically in simple form in Fig. 1. In this figure a control gap 10 is provided with a fuse 11 in series with the control gap and between the control gap and ground. A relief gap 12 is connected in parallel with the fuse 11, the gap 12 being set just high enough that normal voltage will not cause it to arc over after the fuse 11 blows. A condenser 13 is connected in parallel with the fuse 11 and gap 12. If the gap 12 alone were used in parallel with the fuse 11, 40 it is apparent that after the fuse 11 blows, there would be two gaps 10 and 12 in series between the line and ground. This arrangement, of course, would require a higher voltage to produce a flashover than is required with the fuse 11 intact. The purpose of the condenser 13 is to avoid this change in the arcing voltage of the gap due to the opening of the fuse 11. It has been found in practice that a condenser 13 of proper capacity, in parallel with the gap 12, will supply sufficient 45 50 55

charging current to the gap 10 to maintain the flashover voltage of the gap 10 substantially constant, notwithstanding operation of the fuse 11. It is not desirable to have the capacity of the 5 condenser 13 too great as too high a capacity in this condenser tends to maintain a sputtering arc across the gap 10 after the fuse 11 has interrupted the power arc. On most sizes of control 10 gaps for various ratings, it has been found that a capacitance of .0003 microfarad is sufficient to maintain a substantially uniform operation of the gap 10 with any practical gap 12 in series with the gap 10 and with the fuse 11 in place or out. The arrangement shown in Fig. 1 insures continuous 15 protection of the apparatus connected with the gap 10, notwithstanding operation of the fuse 11 to interrupt the power arc following flash-over of the gap 10. It will be apparent, however, that after one operation of the fuse 11 there is nothing to interrupt a second power arc in case 20 flash-over occurs a second time before the fuse 11 has been replaced. However, the arrangement shown in Fig. 1 would operate satisfactory in all cases except those where a second surge follows 25 closely after the first and before the fuse 11 can be replaced. Even in that case the device affords protection for the apparatus since the second surge will flashover the gap 10 and the series gap 12, at substantially the same voltage as the original flashover, but in the case of the second surge, before replacement of the fuse 11, reliance will have to be placed upon the main line circuit breaker to interrupt the power arc.

To further reduce the number of possible interruptions, the arrangement shown in Fig. 2 may be used. In this figure a set of any number of fuses 14, 15 and 16 are arranged for successive connection in parallel with the gap 12. A number of different repeating fuse arrangements are 30 available to the trade at present, most of which are operated by a mechanical throw-over switch which automatically operates, when one fuse blows, to connect in an unblown fuse. Such a switch is indicated diagrammatically at 17. With this arrangement of multiple fuses, it is still desirable to provide the relief gap 12 and condenser 13 to insure protection of the apparatus after the last of the multiple fuses has been exhausted. It is also desirable to employ the gap 12 and condenser 13 to insure protection during the time required for the switch to connect in the next fuse 35 after one has blown. The operation of any switch requires an appreciable time and it sometimes happens that a second surge follows so quickly 40 after the first that the intervening time does not permit the connection of the next fuse in the set. With the arrangement shown in Fig. 2, including the condenser 13 and the relief gap 12, the apparatus is afforded protection even though the second surge should follow so quickly that no time 45 is provided for operation of the switch 17. In case of such operation if the switch gap is less than the gap 12, the arc-over will occur across the switch gap and through the next adjacent fuse so that the fuse will operate to break the power arc even though the switch has not yet been closed. If a solid ground connection were provided in place of the last fuse 16, the gap 12 would not be necessary but the condenser 13 50 would still be required to supply charging current and maintain the calibration of the gap in case a surge that blows a fuse is followed immediately by another before the switch has connected in the next adjacent fuse, for during the time the switch is open it forms a second gap in series with

the main gap that would increase the flashover voltage except for the presence of the condenser 13.

Another repeating fuse arrangement is shown in Fig. 3. In this arrangement no reclosing 5 switch mechanism is required but each fuse has a series gap somewhat shorter than the auxiliary gap 12. With this arrangement, it is readily seen that irrespective of the time interval between repeat surges, the next fuse is always ready to 10 function. The gap 21 in series with the fuse 18 can be made very short or may even be omitted or bridged since after the operation of the first fuse 18, the fuse gap itself will be sufficient to prevent arcing across the fuse gap on the normal 15 line voltage imposed upon the fuse gaps by an arc across the gap 10. It is not absolutely essential to have the gaps 22 and 23 of unequal length. However, it is preferred to have them somewhat different in length in order to insure 20 that both will not operate at the same instant, which may be possible on some extreme, heavy lightning strokes.

Fig. 4 shows the arrangement illustrated diagrammatically in Fig. 3 applied to a practical 25 form of arcing gap of the type shown in Austin patent referred to above. In this figure the numeral 24 designates the mounting for the terminal of the gap connected by any suitable means 25 to the line to be protected. The terminals 26 30 and 27 of the gap are provided with control members 28 for adjusting the gap to various operating conditions. The mounting 24 is supported by insulators 29 carried by a grounded base 30. The terminal 27 is carried by a suitable 35 head 31 mounted upon a condenser 32 which also serves to insulate the head 31 from ground. The condenser 32 corresponds to the condenser 13 shown in Figs. 1, 2 and 3. The lower terminal of the condenser 13 is grounded through its supporting standard 33 which is provided with an arcing horn 34.

The head 31 is provided with a plurality of arcing horns 35, 36 and 37 which cooperate respectively with horns 38, 39 and 40 connected to the 45 terminals of fuse members 41, 42 and 43. The gaps between the horns 35, 36 and 37 and their respective fuse members are of varying lengths, the gap between the central members 36 and 39 being the greatest. The horn 34 is in the same 50 vertical plane with the horns 36 and 39 and forms a gap between the horn 36 and ground which is in parallel with the various fuse members and which corresponds to the gap 12 in Figs. 1, 2 and 3. The gaps between the member 36 55 and the members 34 and 39 respectively have substantially the same electrostatic field conditions so as to insure arcing of the gap 36-39 ahead of the longer gap 36-34 to ground. It will be seen that the fuse members 41, 42 and 43 are mounted upon a hinged head 44 which may be swung backwardly into the position shown in broken lines in Fig. 4 to facilitate renewal of the fuses without danger to the operator. A grounding arm 45 is preferably connected to the head 44 in position to engage one of the arcing horns 35 when the head 44 is rotated into its inoperative position. This grounds the head 31 and its connected parts to insure protection to the operator during renewal of the fuses. It has 60 been found desirable to have the individual fuse gaps made of rod or bar ends similar to that of the auxiliary relief gap in order to eliminate any 65 polarity or over-voltage effects which would be liable to cause dissimilar gaps to operate in an 70 75

improper sequence. The operating head 44 for the fuse gaps is mounted on a grounded shaft which may be rotated by any suitable mechanism without endangering the operator. Since the condenser 32 serves the double purpose of condenser and insulating support for the terminal 21, the cost of a gap provided with a condenser is very little greater than a similar gap with the usual insulation for the terminal 21.

10 The flashover voltage of the condenser 32 need be only slightly greater than the flashover voltage of the auxiliary gap between the members 34 and 36.

I claim:

15 1. In a surge arrester the combination with an arcing gap, of a circuit interrupter adapted, when open, to provide an open break in the circuit in which it is connected, said interrupter being electrically connected between one terminal of said 20 gap and ground, and a condenser in parallel with said circuit interrupter between said terminal and ground for supplying charging current to said arcing gap when said circuit interrupter is open, the capacitance of said condenser being 25 insufficient to produce effective reduction in the crest of a surge voltage causing discharge across said gap, but the resistance of the path through said circuit interrupter being low enough to divert the major portion of the surge current from 30 said condenser and to provide a substantially direct ground for said current.

2. In a surge arrester the combination with an arcing gap, of an overload circuit interrupter adapted, when open, to provide an open break in the circuit in which it is connected, said interrupter being electrically connected between one terminal of said gap and ground for interrupting the power arc following operation of said gap, and means for enabling said gap to operate at approximately the same voltage irrespective of whether said circuit interrupter is open or closed, said means comprising a condenser in parallel with

said circuit interrupter the capacitance of said condenser being not materially more than .0003 microfarad, while the impedance of the path through said circuit interrupter is comparatively, substantially negligible.

3. The combination with an arcing gap, of a circuit interrupter in series with said gap between one terminal of said gap and ground, a condenser in parallel with said circuit interrupter, and an auxiliary gap in parallel with said circuit interrupter and said condenser.

4. The combination with an arcing gap, of a circuit interrupter in series between one terminal of said gap and ground, a condenser in parallel with said circuit interrupter, and an auxiliary gap having a lower flashover value than said condenser in parallel with said condenser and circuit interrupter.

5. The combination with an arcing gap, of an overload circuit interrupter in series between one terminal of said gap and ground, a condenser of approximately .0003 microfarad in parallel with said circuit interrupter, and an auxiliary gap of a lower flashover value than said condenser in parallel with said condenser and circuit interrupter.

6. Means for protecting electrical apparatus from over-voltage impulses comprising an arcing gap having one terminal connected with said apparatus, said gap being adapted to determine the over-voltage impulse at which discharge will occur, a second gap in series with said first-named gap, and a condenser in parallel with said second gap providing capacity between its terminals sufficiently in excess of the capacity between the terminals of said first-named gap so that the predominate portion of an impulse voltage impressed on said gaps in series will be apportioned to said first-named gap to produce flashover at approximately the same voltage as if said condenser were a grounded conductor.

RALPH HIGGINS.
